United States Patent Office

Des. 217,210
Patented Apr. 14, 1970

217,210

TEXTILE FABRIC

Werner W. Rost, Walhalla, S.C., assignor to Cone Mills Corporation, Greensboro, N.C., a corporation of North Carolina

Filed Mar. 3, 1969, Ser. No. 15,996

Term of patent 7 years

Int. Cl. D5—02
U.S. Cl. D92—1

FIG. 1

FIG. 2

FIG. 1 is a top plan view of a textile fabric showing a new design, the fabric is shown over a dark background for purposes of illustration; and

FIG. 2 is an enlarged fragmentary view of the textile fabric.

I claim:

The ornamental design for a textile fabric, as shown and described.
